United States Patent Office

Des. 176,316
Patented Dec. 13, 1955

176,316

PAIR OF SUNGLASSES

Jack F. Fleming, Summit, N. J., assignor to Curtiss-Wright Corporation, a corporation of Delaware

Application December 7, 1953, Serial No. 27,942

Term of patent 14 years

(Cl. D57—1)

The single figure of the drawing is a front perspective view of a pair of sunglasses showing my new design.

I claim:

The ornamental design for a pair of sunglasses, substantially as shown.
